UNITED STATES PATENT OFFICE.

FRANK J. WINTERER, OF PHILADELPHIA, PENNSYLVANIA.

LOAD LIFTER.

Application filed August 2, 1923. Serial No. 655,178.

My invention relates to load lifters and more particularly to an improved oiling system therefor and has for its object to provide means whereby the moving parts of the 5 load lifter will be automatically lubricated during its operation.

This object, and other advantageous ends which will be described hereinafter, I attain in the following manner, reference being 10 had to the accompanying drawings in which

Figure 1 is a vertical longitudinal section partly in full through a load lifter constructed in accordance with my invention,

Figure 2 an enlarged section on line 2—2 15 of Figure 1,

Figure 3 an enlarged section on line 3—3 of Figure 1.

Referring to the drawings, 1 indicates a casing having an oil chamber 2 and a web 3 spaced from the side 4 of the oil chamber.

A sleeve 5 is rotatably mounted in roller bearings 6 and 7. The bearing 6 is integral with the web 3 and the bearing 7 is disposed within the oil chamber and integral with the 25 side 4.

A hoisting drum 8 is keyed to the sleeve and is provided with flanges 9 which have their peripheries 10 bent outwardly. Guards 11 integral with the casing overlie the peripheries 10 so that the cable, which 30 is wound on the drum, will not slip over the flanges. A drum-gear 12 is keyed to the end of the sleeve 5 within the chamber and meshes with a drum-pinion 13 fixed to a

brake-shaft 14 which bears in roller bearings 35 15 within the oil chamber. A drum-brake is mounted on the brake-shaft and comprises a collar 16 slidably keyed to the casing by a lug 17 sliding within a groove 18 on the collar. A friction-wheel 19 is freely mounted

40 on the brake-shaft within the collar and has friction disks 22 mounted on its hub and engaging its sides. A drum-binding-wheel 23 is fixed to brake-shaft 14 and provided with a face 24 which frictionally engages

45 one of the disks 22. A motor-binding-wheel 25 is rotatably mounted on brake-shaft 14 and provided with a face 26 which frictionally engages the other disk. The hub of wheel 25 is provided with a helical cam-

50 ming-face 27 adapted to engage a corresponding camming-face 28 on a collar 29 fixed to brake shaft 14. The term drum-brake will hereafter be used to designate the above structure or a structure having a

55 similar function, that is, to check the racing of the drum when lowering the load.

A motor-gear 30 integral with motor-binding-wheel 25 meshes with a motor-pinion 31 keyed to a motor-shaft 32 which passes through sleeve 5 and has one end 33 rotatable in a roller bearing 34 in the oil chamber and the other end 35 rotatable in a ball bearing 36. Any suitable type of motor 37 may be secured to the casing and connected to the motor shaft. A motor brake of a conventional type for stopping the motor when the current fed thereto is cut off, engages a 60 brake-wheel 38 fixed to motor-shaft 32 and is actuated by a spreader 46 secured to one end of a controller shaft 47 which is actuated by arms 49. Shaft 47 forms a part of 65 a conventional controller and is rockably mounted in a housing 58.

As means for stopping the motor when hoisting a load above the danger point to 70 prevent the load from being raised too near the hoist and wrecking the same, I provide a limit-stop-lever 87 pivoted at 88 and provided with a lug 89 for limiting the downward swinging movement of the lever on its pivot. A lug 90 integral with the lever limits its upward swinging movement. An off-set arm 91, integral with the lever, is adapted to engage a finger 92 integral with the spreader 46. A cable 93 is secured to 75 the drum in any suitable manner and has a hook 94 of any suitable type secured thereto. When the load is raised above the danger point, the hook, or some part connected therewith, will engage the stop lever which 80 will actuate the controller shaft to stop the motor.

The means for suspending the lifter comprise a rectangular bracket 95 provided with a group of similarly spaced holes 96 in each 95 of its sides.

The oiling system includes pockets 101, top oil holes 102 and bottom oil holes 103 in the sleeve-bearing 7 and the motor-shaft-bearing 34. The bottom oil holes 103 lead 100 into pockets 104 and oil holes 105 in the brake-shaft-bearing 15. The motor-shaft 32 is provided with a spiral groove 106 for feeding oil to sleeve bearing 6. The bearing 6 is provided with a cap 107 for sealing it 105 against oil leakage. The oil is splashed from the bottom of the oil chamber into the oil pockets and the spiral groove by a fin-wheel 108 which may be fixed to the shaft or be an integral part of the drum-binding-wheel 110 23. Rotation of motor-shaft 32 will cause the oil to follow the spiral groove into bear-

ing 6 while gravity will cause the oil to flow down from the pockets through the oil holes into the bearings within the oil chamber. The ball bearing 36 is oiled independently 5 of the other bearings by an oil cup or other suitable means. The casing is preferably provided with a cover plate 109 in its end so that access to the interior may be readily had.

- 10 The operation of the load lifter when raising a load is as follows: One of the arms 49 is pulled downwardly which rocks shaft 47 in housing 58 and simultaneously disengages the motor brake from brake-wheel 38 and 15 causes motor 37 to rotate. Rotary movement from the motor shaft is transmitted to the drum through the pinion 31, motor-gear 30, the drum-brake, brake-shaft 14, drum-pinion 13, drum-gear 12 and sleeve 5. 20 This rotary movement is transmitted through the drum-brake as follows: the motor gear 30 will rotate in such direction that camming face 27 will slide on camming face 28 to force motor-binding-wheel 25 against 25 friction disk 22. The drum-binding-wheel 23, being fixed to the brake shaft, will resist this forcing movement, thus resulting in a binding engagement of friction wheel 19 and friction disks 22 between wheels 24 and 30 25. In other words, the collar 29, gear 30, disks 22, friction wheel 19, binding wheel 24 and brake shaft 14 form a unitary structure which rotates as a single unit.

When the load has been raised to its danger point, the hook 94, or some part connected therewith, will engage limit-stop-lever 87 and swing it upwardly. This swinging movement will cause arm 91 to engage finger 92 and rock controller shaft 47 into 35 its neutral position and cut off the current supply to the motor. During this movement of the controller shaft spreader 46 will disengage the motor brake and allow it to grip brake-wheel 38, thereby stopping the 40 motor immediately after the current is cut off. When the load is raised and held in the raised position, the strain is entirely taken up by the drum-brake. The motor brake merely serves as a means to immediately 45 stop the motor when the current is cut off.

To lower the load it is merely necessary to rotate gear 30 in a reverse direction to that for raising the load. This movement of gear 30 will release its binding action against 50 friction disks 22, thereby permitting the load to be lowered. A reverse movement to gear 30 is imparted by a reverse movement of the motor which is produced by rocking shaft 47 in the opposite direction. When 55 the motor rotates in reverse direction to lower the load the rotary movement of the motor shaft will be transmitted to gear 30. If the load should start to travel downward faster than the rotation of the motor, the 60 helical camming face 28 will slide against

cam face 27 forcing gear 30 into binding engagement with disk 22, and thereby retard or completely check the downward movement of the load. Thus the lowering of the 70 load is completely controlled by the lowering of the motor.

During the rotation of the motor, the fin wheel 108 will be rotated at high speed so as to splash oil from the oil chamber, which is filled to a point about midway of the 75 brake shaft, against the roof of the oil chamber and into the pockets and the spiral groove; thus automatically lubricating the load lifter.

If desired the controller may be located on 80 and the lifter controlled from a trailing cage or some point remote from the motor. In such case an electro-magnet would control the motor brake.

A load lifter constructed in the manner 85 above described requires practically no attention in oiling or adjusting after it is installed, the adjustment of the drum-brake and the motor brake being automatic and the 90 parts are readily accessible by simply removing the cover plate.

While I have described my invention as taking a particular form, it will be understood that the various parts may be changed 95 without departing from the spirit thereof, and hence I do not limit myself to the precise construction set forth, but consider that I am at liberty to make such changes and alterations as fairly come within the scope of 100 the appended claims.

Having thus described my invention, what I claim as new and desire to secure by Letters Patent is:—

1. In a load lifter having a casing forming an oil chamber, a roof on the chamber, pairs of bearings for rotating parts disposed one above the other in a chamber, a fin wheel rotatable between a pair of lower bearings and adapted to splash oil against the roof whence it is deflected into the upper 105 bearings which have oil ducts formed in their bottoms whereby oil will pass from the upper to the lower bearings, and means to rotate the fin wheel.

2. In a load lifter having a casing forming an oil chamber; pairs of bearings disposed one above the other in the chamber, all the bearings having oil holes in their tops and the upper bearings having oil holes in 110 their bottoms also, whereby oil may pass from the upper to the lower bearings; a sleeve rotatable in one of the upper bearings and extending into the chamber; a fin wheel rotatable between a pair of lower bearings and adapted to splash oil into the upper 115 bearings and onto the end of the sleeve, and means to rotate the fin wheel.

3. In a load lifter having a casing enclosing rotating parts and forming an oil chamber; a sleeve bearing outside of the chamber; 120

- ber; a sleeve having one end in said bearing and the other end extending into the chamber; a motor shaft passing through the sleeve into the oil chamber and having a spiral groove disposed within the sleeve; bearings in the chamber for the sleeve and motor shaft and having inlet oil holes in their tops and outlet oil holes in their bottoms; rotating parts connecting the motor shaft with the sleeve; bearings for said parts having their inlet oil holes disposed beneath the outlet oil holes of the first mentioned bearings, and means on said parts for splashing oil into the inlet oil holes and into the spiral groove whereby oil will be conveyed to the sleeve bearing outside the chamber. 35
5. A load lifter including a casing provided with an oil chamber and a web at one side of the chamber; sleeve bearings in the chamber and web, the bearing in the oil chamber being provided with an oil hole in its top and bottom; a sleeve rotatable in the bearings; a motor shaft passing through the sleeve into the oil chamber and having a spiral oil groove disposed within the sleeve; a motor shaft bearing for the motor shaft disposed within the chamber and provided with an oil hole in its top and bottom; brake shaft bearings within the oil chamber disposed beneath the sleeve bearing and the motor shaft bearing and provided with an oil hole in their tops for receiving oil from the bottom hole of the sleeve and motor shaft bearings; a brake shaft rotatable in the brake shaft bearings; a fin wheel on the brake shaft for splashing oil from the bottom of the chamber into the holes in the bearings and the spiral groove, and means for operatively connecting the brake shaft with the sleeve and the motor shaft. 40 45 50 55 60
4. In a load lifter having a casing enclosing rotating parts and forming an oil chamber; a sleeve bearing outside of the chamber; a sleeve having one end in said bearing and the other end extending into the chamber; a motor shaft passing through the sleeve into the oil chamber and having a spiral groove disposed within the sleeve; bearings in the chamber for the sleeve and motor shaft and having inlet oil holes in their tops and outlet oil holes in their bottoms; rotating parts connecting the motor shaft with the sleeve; bearings for said parts having their inlet oil holes disposed beneath the outlet oil holes of the first mentioned bearings, and a fin wheel mounted on said

In testimony whereof I have signed my name to this specification.

FRANK J. WINTERER.
